DRYING MACHINE

Clarence A. Wardle, Philadelphia, Pa.

Application May 18, 1934, Serial No. 726,215

1 Claim. (Cl. 34—40)

The present invention relates to laundry machinery and more particularly to driers for curtains, being an improvement upon applicant's Patent No. 1,914,185, granted June 13, 1933.

Some of the objects of the present invention are to provide an improved drying machine for curtains and other articles; to provide a drying machine capable of efficiently handling one or a plurality of curtains to be dried; to provide a drying machine in the form of a unitary structure capable of expanding and contracting as to articles handled in accordance with the drying demanded; to provide a drying machine wherein a plurality of heating elements are employed and are selective for use in accordance with the number of curtains being simultaneously dried; to provide a novel drying machine wherein any one of a number of curtains can be removed and replaced without disturbing others in the machine; and to provide other improvements as will hereinafter appear.

In the accompanying drawing Fig. 1 represents a sectional side elevation of a drying machine embodying one form of the present invention; Fig. 2 represents a section on line 2—2 of Fig. 1; and Fig. 3 represents a section on line 3—3 of Fig. 2.

Referring to the drawing one form of the present invention consists of a box 10 of open top construction and generally rectangular in shape. The length of the box 10 is such as to readily receive a curtain, valance, or other fabric article of maximum length, and of a height to receive the maximum width of such an article. As here shown the two opposite ends of the box 10 are interiorly fitted with built in frames 11 having vertically spaced posts 12 on the inner side forming vertical guideways 13, and vertically spaced columns 14 on the other side forming vertical channels 15. The arrangement is such that guideways 13 in one frame are respectively opposite the guideways 13 in the other frame, and likewise each channel is in alignment with guideway 13 on the opposite side of its frame. The space between each pair of aligned posts 12 is bridged at the top of the box 10 by a beam 16, and the respective pairs of beams 16 are spaced apart a definite distance to permit the placing and removal of the curtain supporting units 17.

These units 17 are preferably all alike, each consisting of a rectangular skeleton frame formed by top and bottom rails 18 and 20, and end mullions 21 and 22. Braces 23 are employed at intermediate locations for strengthening purposes. The work face of each of the rails and mullions is lined with a strip of card cloth 24 so that the

fine teeth thereof can readily penetrate a curtain or other fabric article and hold the article in stretched condition. To ensure proper stretching of such article two stretcher members 25 and 26 are provided, the former being parallel to the mullions and the latter parallel to the rails. The stretcher members 25 and 26 form no part of the present invention since generally they are mounted for sliding adjustment in the manner fully disclosed in the aforesaid Patent No. 1,914,185. Each is faced with card cloth and they are used to stretch the article taut by longitudinal and transverse adjustment.

The units 17 are each mounted between pairs of stiles 27 which are braced at the lower ends by a cross bar 28. The stiles 27 ride vertically respectively in the ways 13 and under control of sash cords 29 and weights 30. As here shown each cord 29 is connected to the lower end of a stile 27 and rides over a pulley 31 located adjacent to the upper end of the channel 15. Pivot pins 32 project from opposite ends of the unit 17 and are respectively journaled in the stiles 27 so that each unit 17 can be swung to a horizontal position when the stiles are elevated to bring the unit 17 above the top plane of the box 10 or top of the other units 17. Each unit 17 is capped by a closure strip 33 along its top edge which strip has a width sufficient to abut the next adjacent strip 33 so that when all the units 17 are in the box 10 the otherwise open top of the box will be entirely closed and the heat confined therein for drying purposes.

For drying purposes each unit 17 is independently heated by a coil 34 located in close proximity to the bottom of the box 10, each coil being below and in direct vertical alignment with its unit 17. As seen in Figs. 2 and 3 the coils 34 are interconnected in series relation having control valves 35 between each pair for cutting certain coils into or out of operation as required. When the units 17 are all within the box 10 the heat from each coil rises vertically to pass through and around each unit 17 with its stretched curtain or valance in position for drying.

For locking each unit 17 in the plane of the stiles 27 and fixed to slide vertically with the stiles 27 each mullion is provided with a spring latching plunger 36 arranged to enter a socket 37 in the adjacent mullion. When any pair of stiles 27 is raised vertically the balance weights 30 allow them to remain in elevated position so that a dried curtain can be removed and replaced by one to be dried. This can be done

expeditiously because the latches 36 can be withdrawn to allow the unit 17 to turn about the pivots 32 and assume a horizontal position whereby the handling and placing of the curtains can 5 take place conveniently.

It will now be apparent that a complete unitary drying apparatus has been devised whereby one or more drying units can be used as desired without waste of either heat or space. Where 10 one unit is to be used steam or other heating medium will be introduced only to the coil 34 directly beneath the unit and so generally considered the box 18 becomes a single unit machine. As other units are brought into use the 15 heating coils respectively for those units are supplied with the heating medium. The novel independent assembly of units makes possible the removal of any desired unit without disturbing the other units and without loss of heat be- 20 cause the bottom plate 40 of each unit seals the opening through which the unit is raised to ele- vated position. Any unit when elevated can be swung to horizontal position for curtain removal or replacement.

While only a single form is shown in which this invention may be embodied, it is to be understood that the invention is not limited to any specific construction, but might be applied to various forms without departing from the 5 spirit of the invention or the scope of the appended claim.

Having thus described my invention, I claim:—

In a drier the combination of an open top box provided with oppositely disposed end ways 10 terminating in the top plane of the box, U-frames mounted therein for vertical sliding movement and in raised position adapted to have the arm portions disposed above the top plane of said box, an article supporting unit carried within 15 each frame, pivotal connections between the unit ends and frame arms to permit the unit to be swung across the arms when the frame is in raised position, and heaters positioned beneath each frame and article supporting unit in the 20 box.

CLARENCE A. WARDLE.
